Hawson & Hawson

UNITED STATES PATENT OFFICE

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA

SPRINKLER HEAD

Application filed December 19, 1928. Serial No. 326,974.

This invention relates to improvements in 5 sprinkler heads of the type employed in fire extinguishing apparatus of the automatic sprinkler type, and the principal object of the invention is to provide a sprinkler head of high efficiency, sensitive, critical in its response to temperature conditions, and not subject to deterioration.

Another object is to provide a novel form 10 of fusible link comprising a plurality of elements maintainable under pressure in predetermined operative relation and adapted to disintegrate upon relief of all or a part of said pressure.

To this end, the invention contemplates 15 provision of a novel form of pressure transmitting link comprising a plurality of compression elements through which said pressure is transmitted, one of which elements is 20 constituted by a fusible composition.

The invention further resides in various 25 novel details of structure illustrated in the attached drawings, in which:

Figure 1 is a side view of a sprinkler head 30 made in accordance with my invention, and

Fig. 2 is a section on the line 2—2, Fig. 1.

With reference to the drawings, the 35 sprinkler head illustrated comprises a vented body member 1 adapted to be inserted by means of screw threads 2 in a sprinkler system. This body member comprises a yoke 3 in the outer end of which and in axial alignment with the passage 4 through the body is a screw 5, see Fig. 2, the screw extending completely through the yoke. The outer end of the screw is provided with a head consisting in the present instance of a plurality of outwardly and upwardly curved fingers 6, this head functioning in obvious manner as a 40 means for turning the screw 5, and also to spread transversely a liquid projected from the discharge passage 4.

The device further comprises a closure 45 element 7 for the end of the passage 4 and a composite link for insertion between the closure member and the inner end of the screw 5 whereby pressure may be exerted by the screw holding the closure element to its seat.

The composite link in a preferred form

comprises a plate 8, one end of which is adapted to seat in a slotted recess 9 in the outer face of the closure member 7, see Fig. 2. This plate 8 has a transverse opening 10 in which in assembly is established a cylindrical 55 receptacle 11 for a fusible compound such as alphanononitronaphthalene. In conjunction with the receptacle 11, I provide a cylindrical plunger 12 adapted for more or less loose insertion in the open end of the receptacle, as shown in Fig. 2, this plunger bearing against the fusible compound. In assembly, the preferably concaved bottom of the receptacle bears against the edge of the aperture 10 and is held against said edge by a pair of 60 compression elements 13, 13 which lie on opposite sides of the plate 8. The lower ends of the elements 13 are confined in a recess in one face of a washer 14, the other face of which bears against the plunger 12, and the 65 upper inwardly offset ends of the elements 13 are similarly confined in a recess in the face of a washer 15, against the other side of which the end of the screw 5 is seated. Preferably, the plunger 12 is recessed for reception of a 70 protrusion on the washer 14, while a similar protrusion on the washer 15 enters a recess in the end of the screw 5, whereby the parts are maintained in proper alignment against 75 any tendency of transverse displacement. 80

It will be noted that contact of the upper end of the plate 8 with the inturned lower ends of the elements 13, 13 tends to separate the latter, this tendency normally being opposed by the washers 14 and 15 in which the 85 ends of said elements are confined. When, however, the fusible compound in the receptacle 11 is fused, the washer 14 is released and the plate 8 through direct contact with the inclined inner surfaces 16 of the elements 13 90 acts as a wedge to separate these elements, thereby effecting a complete disintegration of the link and release of the closure member 7. It will be noted that the fused compound in the receptacle 11 escapes around the sides 95 of the plunger 12, which latter, as set forth above, is only loosely fitted into the outer end of the receptacle.

I claim:

1. A fusible link comprising a pair of 100

transversely separable members, a third member intermediate said pair and constituting a wedge tending to separate said members, and means including a fusible element held under compression between the first named and the third members for confining the ends of the former to prevent said separation.

2. A fusible link comprising a pair of transversely separable members, a third member intermediate said pair and constituting a wedge tending to separate said members, said wedge member having an aperture opposite one end of said paired members, means for normally preventing separation of said paired members including a displaceable element located in said aperture, and a fusible element confined under compression between said displaceable element and the edge of said aperture.

3. A fusible link comprising a pair of transversely separable members, a third member having a direct bearing on said paired members tending to separate the latter, a fusible element confined under compression between said paired and third members and affording an indirect bearing between said members, and means releasable by fusion of said fusible member for normally preventing separation of said paired members.

ARTHUR C. ROWLEY.
